The ornamental design for a process control equipment enclosure, as shown and described.

DESCRIPTION

FIG. 1 is a right side and front perspective view of a process control equipment enclosure showing our new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof, the left side elevational view thereof being identical to the right side elevational view.
